TUBE FRAME FOR LOOMS

John Szczerba, Amsterdam, N. Y., assignor to
Bigelow-Sanford Carpet Co., Inc., Thompson-
ville, Conn., a corporation of Massachusetts

Application February 10, 1933. Serial No. 656,055.

8 Claims. (Cl. 139—10)

This invention relates to tube frames employed for weaving tuft pile fabrics such for instance as Axminster carpets and rugs, and is more particularly directed to the yarn tubes through which the pile forming yarn extends and by which it is presented to the weaving point.

It is now the common practice to provide tube frames with yarn tubes extending therefrom and of generally ovoid shape in cross section. Such 10 yarn tubes have heretofore been assembled on the carrier bar of the tube frame side by side and each has been provided with a mouth or entrance end complete in itself for the yarn.

In weaving tuft pile fabrics of fine pitch it has 15 been found that the dimensional area of the mouth or entrance to the yarn tube frequently interferes with the free passage into the mouth and through the tubes of the pile forming yarn especially when the latter offers any obstruction 20 such as knots or other projections and frequently breakage of the pile forming yarn has resulted necessitating loom stoppage and repair.

One of the objects of the invention is to provide yarn tubes which are not open to the objections heretofore existing and to so construct such tubes that the effective area of the mouth or entrance of the yarn tubes may be substantially and effectively increased, thereby permitting the ready passage of knots or other projections on the pile forming yarn and adapting the tube frame for weaving tuft pile fabrics of finer pitch.

In accordance with the present invention each 25 yarn tube is provided with only one side wall for defining the mouth or entrance to the yarn tubes while the other or opposite wall is constituted by a side wall of the next adjacent yarn tube. In other words, the side walls forming the yarn tube are of different lengths, one extending the 40 full length of the yarn tube while the other or shorter portion of the yarn tube terminates a substantial distance from the upper or entrance end of the yarn tube, the construction being such that when a series of yarn tubes thus constructed are assembled side by side the longer 45 wall of the yarn tube forms one side of the mouth or entrance while the longer wall of the next adjacent yarn tube forms the opposite wall of the entrance.

50 As a further feature of the invention the longer wall of each of the yarn tubes is provided with a laterally extending portion or foot which serves as a means for securing the assembled yarn tubes in their assembled relation. Preferably a series of yarn tubes constructed as above

outlined will be assembled on a backing strip to which they may be secured by solder or otherwise, and then such a backing strip may be attached to the longitudinally extending carrier bar of the tube frame.

60 The invention and novel features thereof will best be made clear from the following description and accompanying drawing of one good form thereof.

Fig. 1 is a front view with some of the parts 65 broken away showing a tube frame containing the present invention;

Fig. 2 is a perspective view of a series of yarn tubes in their assembled relation upon a backing strip;

Fig. 3 is a perspective view at the rear of one 70 of the yarn tubes detached;

Fig. 4 shows the blank from which the yarn tubes may be formed; and

Fig. 5 is a section on the line 5—5 of Fig. 1.

75 The tube frame indicated in Fig. 1 may be of usual construction except as modified by the yarn tubes of the present invention and comprises the longitudinally extending carrier bar 1 from which extend supporting brackets 2 for the yarn carry- 80 ing spool or spools 3, and each of the tube frames of a set is provided with means for detachably connecting it to the usual carrier chains.

As indicated in Fig. 1 the pile forming yarn *a* 85 extends from the spool 3 through the tube frame in separated relation, so that when the tube frame is taken to the weaving point, as usual, by the transerrer the projecting end portions of the pile forming yarn will be introduced between the warp threads.

90 Each yarn tube 4 comprises a tubular body portion which as usual, may be ovoid in cross section and at the top or entrance portion of the yarn tube there is a head 5 of somewhat larger dimension than the tubular body portion of the yarn tube.

One side wall 6 of the yarn tube extends beyond the head and constitutes the longer side of the yarn tube, while the other side portion terminates at a point 7 a substantial distance from 100 the upper or mouth entrance end of the yarn tube, the result being that the two side walls 6 and 7 of each yarn tube are of different lengths and considered separately the mouth or entrance end of the yarn tube has only one side wall 6.

105 The longer side 6 of the yarn tube is provided with a laterally extending portion or foot 8, Figs. 2 and 3, which serves as a means for securing a yarn tube to a backing strip 9. Such backing strips 9 may be formed in convenient lengths and have 110

assembled thereon a desired number of the yarn tubes which may be secured to the backing strip by solder or otherwise by means of the laterally extending portion or foot 8.

5 From the construction thus far described it will be apparent that each yarn tube is formed of a body portion of general ovoid cross sectional shape and an entrance or mouth portion having only one side wall, but when a series of such yarn tubes are assembled together, as indicated in Fig. 2, the side wall 6 of one yarn tube and the longer side 6 of the next adjacent yarn tube will together form the two opposite walls defining the dimensional area of the mouth or entrance to the yarn tube, with the result that the effective area of the mouth or entrance of the yarn tube is substantially and effectively increased, which is of prime importance when weaving fine pitch Axminster fabrics in order to facilitate the passage of knots, etc., into and through the yarn tubes.

Referring to Fig. 5 it will be seen at once that the dimensional area of the mouth or entrance of the yarn tube is defined by the longer walls of the two adjacent yarn tubes.

25 In Fig. 4 a blank is indicated from which the yarn tubes of the present invention may be conveniently formed, although the invention is not, of course, restricted thereto. The blank 10 may be folded along the line 11 to provide a foot or lateral extension 8 projecting from the longer side 6 of the yarn tube. The bends of the blank along the lines 12 and 13 form one portion of the tubular body 4, while the bends along the lines 11 and 14 afford means for connecting the two edge portions of the blank to form the completed tube, as indicated in Fig. 3.

40 While it is preferred to secure or solder a series of yarn tubes on a relatively short backing strip, as indicated in Fig. 2, it is apparent that the lateral extension 8 of the yarn tubes may be connected directly to the carrier bar 1.

45 By forming the entrance or mouth portion of each yarn tube of a single side wall and associating adjacent tubes, as shown, the effective area of the mouth entrance is increased, with the result that any knots or kinks which seek to pass into and through the yarn tubes will not be obstructed thereby, so that breakage of the yarn will be avoided and the assembling adapted for weaving tuft pile fabrics of finer pitch than heretofore.

50 What is claimed is:—

55 1. A yarn tube for tube frames having a mouth or entrance which is formed at one side by a side wall of the yarn tube having a laterally turned foot, and at the opposite side by a wall of the next adjacent yarn tube.

60

75

150

2. A yarn tube for tube frames formed with a tubular body and having a head, the mouth or entrance to which is formed at one side by a side wall of the yarn tube extending beyond the base of the head, and on the opposite side is formed by the side wall of the next adjacent yarn tube which extends beyond the base of the head of that yarn tube. 80

3. A yarn tube for tube frames formed with a tubular body and having a head, the mouth or entrance to which is formed at one side by a side wall of the yarn tube extending beyond the base of the head, and having a laterally extending foot, and on the opposite side is formed by the side wall of the next adjacent yarn tube which extends beyond the base of the head of that yarn tube. 85

4. A yarn tube for tube frames formed with a tubular body and having a head, the mouth or entrance to which is formed at one side by a side wall of the yarn tube extending beyond the base of the head, and having a laterally extending foot, and on the opposite side is formed by the side wall of the next adjacent yarn tube of similar construction which extends beyond the base of the head of that yarn tube, and a backing strip to which the laterally extending feet of the yarn tube are secured. 90

5. A tube frame for weaving tuft pile fabrics, comprising in combination, a carrier member extending longitudinally of the frame, a series of yarn tubes connected to the carrier member, and each having a mouth or entrance for a tuft yarn formed by one upwardly extended side wall of the yarn tube and another side wall terminating a substantial distance below the upper end of the extended side wall to increase the area of the mouth or entrance to the yarn tube. 105

6. A yarn tube for tube frames comprising a tubular body, one of the side walls of which is longer than the other and extends the full length of the yarn tube, so that when a number of such yarn tubes are assembled side by side the mouth or entrance is constituted by the longer side of one yarn tube and the longer side of the next adjacent yarn tube. 110

7. A yarn tube for tube frames having side walls, one of which terminates a substantial distance below the upper ends of the other side wall to form an entrance of increased area. 115

8. A yarn tube for tube frames, one of the walls of which is extended to form a side of the mouth or entrance to the tube frame and the other of which terminates a substantial distance below the upper end of the extended side wall to form an entrance of increased area. 120

JOHN SZCZERBA.
